Primary Examiner — Barbara Fox*Assistant Examiner* — Dana K Weiland(74) *Attorney, Agent, or Firm* — NSIP Law(57) **CLAIM**

We claim the ornamental design for a display screen or portion thereof with icon, as shown and described.

DESCRIPTION

FIG. 1 is a front view of a display screen or portion thereof with icon showing our new design; and,
FIG. 2 is a front view of another embodiment of the display screen or portion thereof with icon shown in FIG. 1.
The dot dash line in the figures represents a boundary line and forms no part of the claimed design.
